PADLOCK

Charles W. Meadowcroft, Sr., Philadelphia, Pa.

Application April 19, 1934, Serial No. 721,325

12 Claims. (Cl. 70—113)

My invention relates to improvements in padlocks and particularly to the type known as keyless, or combination locks.

The object of my invention is to provide a padlock comprising a casing having sections, one of which is rotatable relatively to fixed sections, and providing novel means within the casing for engaging and releasing a shackle by the rotation of the intermediate, or rotatable section.

10 A further object is to provide a novel form of ring bolt which is concealed within a fixed section of the casing, and arranged for engaging the shackle.

15 A further object is to provide novel co-operating means between the rotatable section and the ring bolt for rotating the latter.

A further object is to construct the ring bolt so that both bars of the U-shaped shackle will be held in locking engagement.

20 A further object is to provide a novel arrangement of the markings upon the adjacent sections of the casing whereby only one set of markings can be made to register at the same radial position of the rotatable section.

25 These together with various other novel features of construction and operation of the parts, which will be more fully hereinafter described and claimed, constitute my invention.

Referring to the accompanying drawing:—

30 Fig. 1 is a vertical sectional view of a padlock embodying my invention.

Fig. 2 is a view similar to Fig. 1, showing the parts in the unlocked position.

Fig. 3 is a view in elevation of the padlock 35 showing the novel arrangement of the markings upon the sections.

Fig. 4 is a diagram showing the development of the surfaces of the sections of the casing and illustrating the arrangement of the markings.

40 Fig. 5 is a perspective view of the parts of the padlock, detached.

Fig. 6 is a section on line 6—6 Fig. 7.

Fig. 7 is a vertical section of a lock showing a different form of my invention. Fig. 8 is a 45 side elevation of Fig. 7.

In the accompanying drawing, in which like reference characters refer to like parts, 10 represents a casing, or housing, preferably formed of stamped metal, and comprising a main section 50 12, and a lower section 13, embracing an intermediate section. The sections 12 and 13 are of cup shaped formation, having disks 14 and 15, and cylindrical walls 16 and 17, respectively. The disk 14 is provided with a depressed portion 55 rounding a centrally located aperture, which is

occupied by one end of a post 20, extending axially through the casing. The post 20 has reduced portions 21 and 22 formed with roughened surfaces, which fit tightly into the apertures formed in the end disks. Heads are formed by riveting 60 the ends of the post upon the disks and rigidly secure the end sections upon the post.

The disk 14 of the main section 12 is provided with apertures 24 and 25 to receive a shackle 26, having bars 27 and 28, which extend through said 65 apertures in parallel relation to the post 20.

The lower end section 13 is similar in construction to the section 12. In the form shown in Figs. 1 to 5 the section 13 is provided with a cup shaped cap 29, rigidly secured, by brazing, to the wall 70 17, of section 13.

The disk 15 of the section 13 is provided with an aperture 30 through which the longer bar of the shackle extends and is guided by the disk 15. The bar 28 has an enlarged end 31, which 75 engages the disk 15, for limiting the upward movement of the bar, as shown in Fig. 2.

An intermediate section 35, has a cylindrical wall 36, which is positioned between the end sections 12 and 13. Said sections have annular shoulders 37, 38, and 39, of smaller diameter than the cylindrical walls of the sections. The shoulders 37 and 38 are fitted within the adjacent sections and are loosely mounted in the walls of the next adjacent sections. Annular bearings 80 are thus formed upon which the section 35 is rotatably mounted between the end sections 12 and 13 and also held in axial alignment with the end sections.

The section 35 is provided with an annular, inwardly projecting, flange 40. The bar 28 of the shackle has a recess 41 formed therein which is occupied by the flange 40, thus locking the bar 28 within the casing. The flange 40 is rotatable through the recess 41 formed in the bar, and 90 said flange 40 is provided with a recess, or gating 42, through which the bar 28 may freely pass when the section 35 is rotated to a position in which the gating will register with the bar 28.

A ring bolt 45, having a cylindrical wall 46, and an annular inwardly projecting flange 47, is concealed within the main section 12. The ring bolt is rotatably mounted within the cylindrical wall 16 of the section 12.

The ring bolt is formed of spring metal, and it is split at 48, so that the wall 46 will tend to bind against the wall 16 and prevent accidental rotation of the ring bolt.

The ring bolt 45 is positioned between the inner bearing surface of the shoulder 39 formed 110

on section 12, and the flange or the shoulder 37 of the intermediate section 35. Said shoulders 37 and 39 form thrust bearings for the ring bolt, and the shoulder 39 positions the ring bolt 5 in spaced relation to the disk 14 of the main section 12.

The inwardly projecting flange 47, of the ring bolt, embraces the bars 27 and 28 of the shackle. Said bars have recesses 50 and 51 formed therein, 10 which are occupied by the flange 47 for locking said bars. The flange 47 is provided with recesses, or gatings 52 and 53, through which the bars 27 and 28 may freely pass, when the ring bolt is rotated to align said gatings with said bars.

15 The intermediate section and the ring bolt 45 are provided with co-operating parts and arranged for rotating the ring bolt by the movements of the intermediate section. A projection, or tongue 55 is located upon the intermediate section 35, and the cylindrical wall 46, of the ring bolt, is provided with a notch 56, which is occupied by the tongue 55. The tongue engages the cylindrical wall 46 at either end of the notch 56, by 20 which arrangement the ring bolt may be rotated by the section 35. The notch 56 is of greater length than the width of the tongue 55, so that the section 35 may have a partial rotary motion in relation to the ring bolt, without rotating the latter.

25 30 The flanges 40 and 47 have the gatings therein so located that the gatings will be staggered when the tongue 55 is in engagement with the ring bolt at either end of the notch 56, thus retaining the shackle locked within the casing.

35 The shackle is released from the intermediate section 35 by turning the latter to a given position, as shown by the markings on the outer surfaces of the sections. During the movement of the section 35, the tongue 55 engages and rotates the ring bolt to a position in which the 40 gatings 52 and 53 in the flange 47, of the ring bolt, will register with, and release, the bars 27 and 28 from the ring bolt. The section 35 is then rotated in a reverse direction, in which the 45 tongue 55 will move in the notch 56 without turning the ring bolt. When the section 35 is so turned in the reverse direction until certain other markings register, the gating 42 in the flange 40 will align with the bar 28 and the latter will be released from the intermediate section 35. The 50 shackle is thus entirely released from the flange 40 of the section 35 and from the flange 47 of the ring bolt, and may be withdrawn from the casing, as shown in Fig. 2.

55 Fig. 4 illustrates the arrangement of the markings upon the sections of the casing. The end sections 12 and 13 are shown with ten spaces between the markings 60 and 61. The intermediate section 35 is provided with nine spaces between the markings 62. Unequal space relations are thus formed between the markings upon the 60 fixed sections 12 and 13, and the markings upon the rotatable section 35. The markings upon the sections are arranged similar to the markings upon a vernier scale. By this arrangement only one set of markings on the different sections can be made to register at one time, as shown at F. O. X. Fig. 4. The unequal spaces between the markings of the different sections make it 65 more difficult to open the lock when the combination is unknown.

70 Figs. 6 to 8 illustrate another form of my invention. This construction is particularly adapted for locks having the casing sections formed of cast metal. The end sections 71 and 72 are of

hollow cup shaped formation and they are inverted and rigidly secured together by a central post 73, thus forming a hollow chamber throughout the length of the casing. The intermediate section 74 is provided with two annular flanges, or shoulders, 75 and 76, which are rotatably mounted upon the cylindrical walls of the end sections 71 and 72.

80 The end section 72 is provided with a post 77, which loosely enters a bore formed in the inner end of the bar 78 of the shackle 79, thus forming a guide for the inner end of the bar 78.

A ring bolt 80 is rotatably mounted in the section 71. The ring bolt is split at 81 which allows it to bind sufficiently within the section 71 to prevent the accidental rotation of the ring bolt.

85 The intermediate section and the ring bolt have co-operating parts in the form of a projection 82 on the intermediate section, and a notch 83, formed in the ring bolt, and occupied by the projection 82. The flanges 85 and 86 interlock with the shackle in a manner similar to the lock shown in Figs. 1 to 4, and above described.

90 The central post 73 is provided with a radial bearing 88, in which is mounted a pin 89. A spring 90 urges the pin against the inner cylindrical wall of the section 74. The latter is provided with recesses 91 to partially receive the end of the pin. When the section 74 is rotated the pin will be moved over the surface of the wall 95 of section 74 and the end of the pin will enter the recesses 91 and make sufficient sound, or vibration, so that the operator can determine the relative position of the sections by counting the recesses over which the pin passes.

100 The section 74 has the series of recesses 91 arranged with one recess 92, see Fig. 7, made larger, or spaced at a different distance from the other recesses, so that said recess 92 can be used as a starting position from which to count the 105 recesses as the section 74 is rotated. By this arrangement all markings upon the outside of the lock may be eliminated.

110 The operation of my invention is as follows: The shackle is locked by pushing the bars into the 115 casing and rotating the intermediate section in either direction. In the form shown in Figs. 1 to 5 the shackle is released by rotating the intermediate section 35 to register the predetermined markings of the combination, such as E. O. W.—120 F. O. X. This combination being known, the first operation to open the lock is to turn the section 35 to the left until the markings E. O. W. register. This movement will cause the tongue 55 on the section 35 to rotate the ring bolt 45 to a position in which the gatings 52 and 53 will register with and release the shackle bars from the ring bolt. The second operation is to rotate the section 35 in the reverse direction until the markings F. O. X. register. This movement will bring the gating 42 of the flange 40 into alignment with the bar 28, and entirely release the shackle. Said reverse movement does not move the ring bolt, as the tongue is free to move in the notch 56 of the ring bolt.

125 130 135 The markings G. O. Y. and F. O. X. may also be used for the same combination of the lock. In this case, to open the lock, the first operation would require the intermediate section 35 to be rotated to the right until the markings G. O. Y. register and release the shackle from the ring bolt. The second operation would require a reverse movement of section 35 until the markings F. O. X. register and release the shackle.

140 145 150 The lock shown in Figs. 6 to 8, is opened by

first rotating the intermediate section 74 until the pin 89 enters a certain recess 92, indicating the starting position. Then the section 74 is turned, first in one direction and then in the 5 other direction, to certain predetermined positions, and the shackle will be released.

Various changes in the construction and arrangement of the parts may be made without departing from my invention.

10 I claim:—

1. A padlock having in combination, end sections, an intermediate section rotatably mounted between the end sections, said end sections being of hollow cup shaped formation, a post 15 upon which the end sections are rigidly mounted, a shackle having a part extending into said sections, a ring bolt rotatably mounted within an end section, interlocking means upon the ring bolt and the shackle, and co-operating parts upon

20 the intermediate section and the ring bolt and arranged for engaging and disengaging the latter from the shackle.

2. A padlock having in combination, an intermediate section, said section having a cylindrical 25 wall, end sections located upon opposite ends of the cylindrical wall, means rigidly securing the end sections together in spaced relation to each other, annular bearing surfaces upon said end sections upon which the intermediate section is 30 rotatably mounted, a shackle having a bar extending into said sections, a ring bolt rotatable within an end section, interlocking means upon the ring bolt and the shackle bar, and co-operating parts upon the intermediate section and 35 the ring bolt and arranged for rotating the ring bolt relatively to the shackle.

3. A padlock having in combination, end sections, cylindrical walls upon said sections, a post 40 upon which the end sections are rigidly mounted, an intermediate section positioned between said walls, an annular shoulder upon the intermediate section and extending into the wall of an end section and rotatably mounting the intermediate section, a ring bolt rotatably mounted within an 45 end section, said bolt having a notch formed therein, a projection upon the intermediate section and positioned within said notch, an internal flange upon the ring bolt, a shackle having a recess formed therein to receive said flange, and said 50 flange having a gating formed therein for the free passage of the shackle.

4. A padlock having in combination, end sections of cup shaped formation, a post upon which the end sections are rigidly secured, an intermediate section rotatably mounted between the end sections, a shackle having parallel bars extending into one end section, a ring bolt positioned within an end section and rotatable therein, an annular 55 inwardly projecting flange upon the ring bolt, said bars each having recesses formed therein to receive said flange, said flange having gatings formed therein for the free passage of said bars, and co-operating parts upon said intermediate section and said ring bolt and arranged for rotating the latter by the rotation of the intermediate section.

5. A padlock comprising end sections, an intermediate section rotatably mounted between the end sections, a shackle, interlocking means between said intermediate section and the shackle, a ring bolt rotatably mounted and concealed within said sections, interlocking means between the ring bolt and the shackle, and co-operating parts upon said intermediate section and said ring bolt

for engaging and disengaging the latter from the shackle.

6. A padlock comprising, cylindrical end sections, a post upon which the end sections are rigidly secured, an intermediate section positioned between and rotatable upon an end section, a ring bolt rotatably mounted within an end section, a shackle having a bar extending into one end section and surrounded by the intermediate section and by the ring bolt, an annular inwardly projecting flange upon the intermediate section and arranged for engaging said bar, an annular internal flange upon the ring bolt and arranged for engaging said bar, said flanges having gatings formed therein through which the bar may freely pass, 80 and cooperating parts upon said intermediate section and the ring bolt and arranged for rotating the latter by the rotation of the intermediate section.

7. A padlock comprising, a cup shaped end 85 section, a post rigidly secured to said section, a section secured upon the opposite end of said post, an intermediate section rotatably mounted between said sections, a ring bolt rotatably mounted within said end section, a shackle bar extending 90 into said end section, annular flanges upon the intermediate section and upon the ring bolt and arranged for engaging said bar, a projection upon the intermediate section, said ring bolt having a notch formed therein and occupied by said projection, said notch having sufficient length to permit the projection to have a partial rotary movement independently of the ring bolt, said flange on the ring bolt having a gating formed therein and radially positioned thereon for the free passage of said bar when the ring bolt is rotated to a given position by said projection, and said flange on the intermediate section having a gating formed therein and radially positioned thereon for the free passage of said bar when the intermediate 100 section is rotated in a direction to move the projection in said notch without moving the ring bolt.

8. A padlock comprising, a main end section

of hollow formation, a post secured to said section, an end section secured to the opposite end of said post, an intermediate section rotatably mounted between the end sections, a shackle having parallel bars, a ring bolt rotatably mounted in the main section, an annular flange upon the 120 ring bolt, said shackle bars each having recesses formed therein to receive said flange, said flange having gatings formed therein for the free passage of said bars, an annular flange upon the intermediate section, one of said bars 125 having a recess therein to receive the last mentioned flange, said last mentioned flange having a gating therein, co-operating parts upon the intermediate section and the ring bolt for rotating the latter, and said gatings located in staggered relation to said parts.

9. A padlock comprising, hollow cylindrical end sections, an end disk upon each section, a post secured between said disks and rigidly holding the sections in spaced relation, an intermediate 140 section positioned between the end sections, annular interlocking shoulders upon said sections rotatably mounting the intermediate section upon the end sections, a shackle having parallel bars, one of said end disks having apertures formed 145 therein for the passage of said bars, a post upon the opposite end disk and forming a guide upon which one of the bars of the shackle is slidably mounted, an annular flange upon the intermediate section, one of said bars having a recess 150

formed therein and occupied by said flange, said flange having a gating formed therein for the free passage of the bar, a ring bolt rotatably mounted within an end section, an annular flange 5 upon the ring bolt, said bars having recesses formed therein to receive the last mentioned flange, said last mentioned flange having gatings formed therein for the free passage of said bars, and co-operating parts upon the intermediate 10 section and the ring bolt and arranged for rotating the latter by the rotation of the intermediate section.

10. A padlock comprising, a cylindrical main section, a shackle mounted upon said section, a 15 cylindrical section rotatably mounted in axial relation to the main section, a series of markings upon each section, the markings upon the rotatable section having a different space relation between the markings relatively to the space relation 20 between the markings upon the main section, co-operating locking means between the rotatable section and the shackle, a ring bolt rotatably mounted within the main section, co-operating locking means between the ring bolt 25 and the shackle, and engaging means upon said rotatable section and upon the ring bolt and arranged for rotating the latter by the rotatable section and for releasing the shackle when predetermined markings of said sections register.

30 11. A padlock comprising, a casing, a cylin-

drical wall upon the casing, a shackle mounted upon the casing, a bar upon the shackle extending axially relatively to said wall, a rotatable section, means rotatably mounting the latter upon the casing, a ring bolt of split formation mounted within said cylindrical wall, interlocking means upon the ring bolt and the shackle, and co-operating parts upon the rotatable section and the ring bolt and arranged for engaging and disengaging the latter from the shackle.

12. A padlock comprising, end sections, cylindrical walls upon said sections, a post upon which the end sections are rigidly mounted, an intermediate section positioned in axial alignment with said walls, means rotatably mounting the intermediate section between said end sections, a ring bolt of split formation, a cylindrical wall upon said bolt and rotatably mounted within the cylindrical wall of an end section, said last mentioned wall and said wall of the ring bolt being in frictional contact to retard the rotation of the ring bolt, a shackle having a part extending within said sections, interlocking means upon the ring bolt and the shackle, and co-operating parts upon the intermediate 100 section and the ring bolt and arranged for engaging and disengaging the latter with the shackle.
